Primary Examiner — Sandra Snapp**CLAIM**

The ornamental design for a scent module, as shown and described.

DESCRIPTION

FIG. 1 is a perspective view showing one embodiment of the scent module;

FIG. 2 is a front view of the scent module of FIG. 1;

FIG. 3 is a rear view of the scent module of FIG. 1;

FIG. 4 is a left side view of the scent module of FIG. 1;

FIG. 5 is a right side view of the scent module of FIG. 1;

FIG. 6 is a top view of the scent module of FIG. 1; and,

FIG. 7 is a bottom view of the scent module of FIG. 1.

The broken lines appearing in FIGS. 1-7 define the bounds of the claimed design and/or disclose environment related to the claimed invention, and therefore form no part of the claimed design.
